INVENTOR

UNITED STATES PATENT OFFICE

96,741

DESIGN FOR A BLOUSE

Harry Glaser, New York, N. Y.

Application August 7, 1935, Serial No. 57,984

Term of patent 3½ years

To all whom it may concern:

Be it known that I, Harry Glaser, a citizen of the United States of America, residing in Manhattan, county of New York, and State of New York, have invented a new, original, and ornamental Design for a Blouse, of which the following is a specification, reference being had to the accompanying drawing, forming part thereof, wherein,

The parallel lines extending from the sides of the neckline to the yoke member of the blouse represent superimposed cording.

I claim:

The ornamental design for a blouse, substantially as shown and described.

HARRY GLASER.
